UNITED STATES PATENT OFFICE.

SOREN CHRISTIAN REFSHOLDT, OF SOUTH OMAHA, NEBRASKA.

SCOURING ATTACHMENT FOR BOATS.

1,181,251.

Specification of Letters Patent.

Patented May 2, 1916.

Application filed May 13, 1915. Serial No. 27,918

To all whom it may concern:

Be it known that I, JOHN CHRISTIAN REPSHOLDT, a citizen of the United States of America, residing at South Omaha, in the county of Douglas and State of Nebraska, have invented certain new and useful Improvements in Sounding Attachments for Boats, of which the following is a specification.

10 This invention relates to new and useful improvements in sounding attachment for boats.

The primary object of this invention is the provision of an attachment upon such crafts as river boats whereby the presence of shoals may be readily determined when the boat is running through muddy water and thus prevent the grounding of the boat.

20 A further object of the device is to provide a forwardly positioned shoal finder capable of sounding a bell in the pilot house whenever a shoal is encountered, the boat also being provided with adjustable sounding attachments at the opposite sides thereof for 25 the purpose of determining the position and extent of the shoal.

It is a further object in connection with such a device to arrange shoal finders swivelly mounted upon a boat deck and readily elevated out of the water when not desired for use, the sounding portion thereof being adapted to automatically feather during a lateral shifting of the device.

With these general objects in view and
others that will appear as the nature of the
invention is better understood, the same
consists in the novel combination and ar-
rangement of parts hereinafter fully de-
scribed, illustrated in the accompanying
drawings and pointed out in the appended
claims.

45 In the drawings forming a part of this application and in which like designating characters refer to corresponding parts throughout the several views:—Figure 1 is a perspective view of the forward portion of a boat positioned in the water and provided with the present invention, one of the sounding elements being shown in dotted lines in its inoperative elevated position and another of the same being shown in dotted lines shifted to a position adjacent the side of the boat. Fig. 2 is a vertical central sectional view of one of the shoal finding devices, the blade thereof being broken away. Fig. 3 is a top plan view of

a portion thereof, and Fig. 4 is an enlarged side elevation of the sounding means partly broken away and in its indicating position.

Referring more in detail to the drawings, the boat 10 is herein illustrated provided with one of the devices positioned at the bow 11 of the deck 12 thereof and with two of the devices oppositely arranged at rearward points upon the deck, the said boat having a pilot house 13.

The forward and side shoal finders are identically constructed with the exception that the forward finder is not swivelly mounted upon the deck and is also provided with a bell ringing attachment so that the remaining elements being the same, the description thereof is identical. 70

The present shoal finding means consists of a tubular arm 14 having a hinged connection 15 with a circular disk 16 supported by the deck of the boat. A tubular rod 17 is journaled within a sleeve 26 and said sleeve is hinged as at 18 to the outer end of the said arm and has a bar 19 longitudinally slidable therein and slightly projecting from the upper end of the said rod 17. A blade 20 is hinged as at 21 to the lower end of the rod 17 and has its inner end connected as at 22 with a wire connector 23, the upper end of which connector is secured to the lower end of the slidable bar 19. A helical spring 24 is positioned within the rod 17 surrounding the wire 23 and seated between the lower end of the bar 19 and an annular shoulder 25 of the rod 17. Similar 75 80 85 90

annual shoulder 25 of the rod 17. Similar oppositely arranged locking bolts 27 are slidably positioned within the arm 14, one being engageable with the hinge connection 15 and the other with the hinge connection 18 while an intermediate spring 28 normally retains the said bolts in their projected locking positions. A bracket 29 is mounted upon the arm 14 and has a cam lever 30 pivoted thereto while connections 31 are arranged between the said lever and the bolts 27 in such a manner that a movement of the free end 32 of the lever 30 away from the carrying arm 14 retracts both of the bolts 27, thus allowing the arm 14 and rod 17 to move to their substantially vertical inoperative position, as shown at the starboard side of the boat in Fig. 1 of the drawings. A cord 33 is attached to the lever end 32 and terminates as at 34 within the pilot house 13.

It being understood that each of the shoal

indicating means positioned either forwardly or at the side of the boat is provided with a similar cord 33, it will be seen that when the pilot desires to elevate any one of the three shoal finders to its inoperative position, it is only necessary to pull upon the cord end 34 for the desired finder, when the lever 30 will release the bolts 27 and a further pull upon the cord will elevate the arm 14 upon its hinge 15 substantially vertically, while the weight of the blade 20 will allow the rod 17 to move to a vertical position upon its hinge 18 and lie along side of its carrying arm 14, the entire device being then positioned at the gunwale of the boat.

The usual manner of operating the entire invention is for the boat to proceed ahead at full speed with the forward finder operatively positioned in the water, but with the two side finders in their folded inoperative positions. When a shoal is encountered by the blade 20 of the forward finder, the blade is moved upon its hinge 21 which lowers the wire 23 and bar 19 so that the lug 35 provided upon the bar of the forward finder will engage a pivoted lever 36 mounted upon the rod 17 of the forward finder, thus shifting the lever and exerting a pull upon a cord 37 connected to the free end of the lever and passing across the deck into the pilot house 13 and having its inner end operatively attached to an alarm bell 38 within the pilot house. The bell 38 being rung in this manner whenever the blade 20 of the forward finder strikes a shoal, the speed of the boat will then be reduced as may be desirable and the cord ends 34 will be operated for allowing the side finders to drop of their own weight to their operative positions in the water. The side finders constituting feelers will then be employed for determining the position of the shoal and the depth of water covering the same, it being noted that the side finders are laterally shiftable by the means hereinafter described, the said side finders acting as feelers and the forward finder acting also to give a warning alarm. It will also be noted that the hinge connection 18 of the arm 14 of the forward or bow finder is with the rod 17 rather than with the sleeve 26, as is the case in connection with the side finders or feelers which are self feathered.

The disk base 16 of each of the side finders or feelers is swivelly mounted on the deck 12 by means of a centrally arranged pivot bolt 39, while an intervening stationary disk 40 is arranged between the base disk and the deck. This disk 40 is provided with a vertical socket 41 and the base disk 16 carries a shiftable pin 42 extending therethrough, the said pin being adapted for seating within the socket 41 when the side finder is shifted laterally adjacent the gunwale

of the boat as shown in dotted lines in Fig. 1, it being understood that the pin 42 is normally positioned within the socket 43 of the stationary disk 40 when the side finders are laterally arranged, while either of the sockets 41 or 43 may be employed when the side finders are in their elevated folded positions. The rods 17 of the side finders being swiveled within the sleeves 26, the said rods are each provided with a cross piece 44 having its opposite ends connected by cords 45 with upright posts 46 mounted upon the boat deck 12 adjacent the base disk 16 of the finder. By this arrangement, a shifting of the arm 14 of the side finders or feelers to their forward positions will cause the blades 20 thereof to constantly maintain their same direction in the water which is that of feathering so as to offer less resistance during the travel of the boat.

As before stated, when an alarm is given by the forward finder, side feelers may be lowered into the water and will engage the adjacent shoal or sand-bar and by the position of the frames constituting the side feelers, the lateral position of the shoal may be easily determined. During such lowering movement, the blades 20 will engage the adjacent side shoal and the lowering movement of the frame will be stopped, which will indicate the side position of the shoal and by the hinged connection of the blade to the rod 17, injury to the side frames will be prevented as the forward movement of the boat will cause the blades to move on their hinged connection with the said rod.

It will thus be seen that a serviceable and efficient shoal indicating alarm and detector is provided for boats adapted to travel especially in muddy and shallow water.

While the form of the invention herein shown and described is what is believed to be the preferred embodiment thereof, it is nevertheless to be understood that minor changes may be made in the form, proportion and details of construction without departing from the spirit and scope of the invention as set forth in the appended claims.

What I claim as new is:—

1. A shoal finder for a boat comprising a disk base mounted on the boat, a tubular arm hinged to the said base, a tubular rod hingedly connected to the opposite end of the said arm, a bar slidably mounted within the said rod and projecting outwardly of the upper end thereof, a blade hinged to the lower end of said rod and having its upper end arranged therein, a connecting wire between the adjacent ends of the said blade and bar, an expansible elevating spring for the said bar arranged within the rod, and releasable locking means for the said arm hinges.

2. A shoal finder for a boat comprising

a disk base mounted on the boat, a tubular arm hinged to the said base, a tubular rod hingedly connected to the opposite end of the said arm, a bar slidably mounted within the said rod and projecting outwardly of the upper end thereof, a blade hinged to the lower end of said rod and having its upper end arranged therein, a connecting wire between the adjacent ends of the 5 said blade and bar, an expansible elevating spring for the said bar arranged within the rod, locking bolts for the arm hinges slidably arranged within the said arm, a projection spring for the said bolts arranged 10 therebetween, a cam lever pivoted upon the said arm, operative connections between the said lever and bolts, and an operating cord extending from the free end of the said lever to a point upon the boat.

15 3. A shoal finder for a boat comprising a disk base mounted on the boat, a tubular arm hinged to the said base, a tubular rod hingedly connected to the opposite end of the said arm, a bar slidably mounted within the said rod and projecting outwardly 20 of the upper end thereof, a blade hinged to the lower end of said rod and having its upper end arranged therein, a connecting wire between the adjacent ends of the said blade and bar, an expansible elevating 25 spring for the said bar arranged within the rod, locking bolts for the arm hinges slidably arranged within the said arm, a projection spring for the said bolts arranged therebetween, a cam lever pivoted upon the 30 said arm, operative connections between the said lever and bolts, an operating cord extending from the free end of the said lever to a point upon the boat, a side lug provided upon the said bar, a lever pivoted to the said rod and having one end arranged in the path of movement of the said lug, an alarm bell upon the boat and an operating cord connected between the said bell and the free 35 end of the said lever.

4. A shoal finder for a boat comprising a disk base mounted on the boat, a tubular 40 arm hinged to the said base, a tubular rod hingedly connected to the opposite end of the said arm, a bar slidably mounted within the said rod and projecting outwardly of the upper end thereof, a blade hinged to the lower end of said rod and having its upper end arranged therein, a connecting wire between the adjacent ends of the said blade and bar, an expansible elevating 45 spring for the said bar arranged within the rod, locking bolts for the arm hinges slidably arranged within the said arm, a projection spring for the said bolts arranged therebetween, a cam lever pivoted upon the 50 said arm, operative connections between the said lever and bolts, an operating cord extending from the free end of the said lever to a point upon the boat, a side lug provided upon the said bar, a lever pivoted to the said rod and having one end arranged in the path of movement of the said lug, an alarm bell upon the boat and an operating cord connected between the said bell and the free 55 end of the said lever.

5. A shoal finder for a boat comprising a base disk swivelly mounted upon the deck thereof, a stationary disk underlying the said base disk and provided with a plurality of sockets, an adjusting pin extending through the said base disk and adapted for seating within the said sockets, an arm upon the said base disk, a sleeve at the outer end of said arm, a rod journaled within the said 60 sleeve, a blade connected to the lower end of the rod, and manually controlled means associated with the hinged arm and sleeve for locking and unlocking the same.

In testimony whereof I affix my signature.

SOREN CHRISTIAN REPSHOLDT.
